HEAD-POSITIONING DEVICE FOR X-RAY PHOTOGRAPHY

Anthony G. Dasta and Edward L. Curran, both of
2716 N. Central Ave., Chicago, Ill. 60639
Filed Dec. 13, 1965, Ser. No. 513,371
1 Claim. (Cl. 248—118)

ABSTRACT OF THE DISCLOSURE

A bracket fitted with a back portion in the cassette support of an X-ray apparatus, the bracket projecting a frontal plate in forwardly-inclined direction for receiving the cassette. A brace is secured between the back portion and the lower part of the plate.

Our invention relates to cassette supports for taking X-ray pictures of the human jaw, and comprises a backing plate adapted to receive the cassette and fitted to the support. The plate projects at an angle for the sidewise application of the jaw, whereby to separate the exposure of the teeth on one side of the jaw from that of the teeth on the other side thereof.

Our object is to provide a device which may be mounted by simple sliding action in the wall chest bracket of the X-ray equipment to present an inclined backing plate for the X-ray cassette to position the head of the patient at the required tilt for taking the picture as stated.

A better understanding of the invention may be gained by reference to the accompanying drawing, in which

FIG. 1 is a face view of a fragment of the wall chest bracket, showing the novel head-positioning device mounted thereon;

FIG. 2 is a view from the left-hand side of FIG. 1, showing the device equipped with the X-ray cassette and the patient's head applied to the latter;

FIG. 3 is an enlarged front view of the device; and

FIG. 4 is an enlarged side view thereof as seen in FIG. 2.

Referring specifically to the drawing, 10 denotes the uprights of the wall chest bracket as a pair of tubes; and 11 and 12 denote upper and lower cross-heads of the bracket, with end blocks 11a and 12a slidable on the tubes to desired positions where they remain stationary by friction or suitable clamping means (not shown).

The cross-heads 11 and 12 are designed for supporting the plate 15 of the jaw-positioning device, and are therefore adjusted in vertical spacing according to the height of such plate. At the rear the latter has a top crown 15a and a bottom foot 15b. The cross-heads 11 and 12 carry channel flanges 11b and 12b in which the plate crown 15a and foot 15b fit as shown in FIG. 2 when the plate is inserted by lateral movement into the flanges.

The plate 15 is of heavy plastic material, and has a vertical back section 15c connecting the crown 15a and the foot 15b. In front, the crown is projected with a short ledge 15d from which the plate 15 extends at an angle of approximately 45 degrees to the back section 15c, the plate terminating at the bottom with a short forward

2

flange 15e. The X-ray cassette 18 is laid on the plate 15 as shown in FIG. 2, and is supported at the bottom by the plate flange 15e.

In order that the plate 15 may be positioned rigidly at all times, it is reinforced on the inside by a brace 20. The latter is of the same material as the plate but narrower, as seen in FIG. 3. The brace has an inclined flange 20a in front backing the plate 15, and a downflange 20b at the rear seating against the back section 15c. The downflange is attached to the latter by a pair of round-headed rivets 22 of plastic material; and the inclined flange is attached to the plate 15 by similar rivets 23 with round heads 23a on the rear side and flat heads 23b in front, as seen in FIG. 4.

When the device is mounted as shown in FIGS. 1 and 2, it is positioned at the proper angle to receive the patient's head tilted as shown in FIG. 2. The jaws of the patient are now staggered or apart in vertical relation, so that the rays from a projector at the right (not shown) will procure pictures of both jaws during a single exposure.

It will now be apparent that the novel head-positioning device is a simple means for procuring the desired X-ray picture with dispatch and comfort to the patient, since it dispenses with the need for the patient to lie down, and a table and sand bags or other makeshift accessories to position the patient's head at the proper tilt. At the same time, the device is readily adapted to the conventional wall chest bracket by simple lateral insertion, and without the need of attaching devices or tools. Finally, the device is sturdy, handled in one piece, and of a nature to be produced at low cost.

We claim:

1. A device for positioning the head of a person of erect posture for taking an X-ray picture of the jaws from one side, comprising a plate adapted to receive an X-ray cassette on said side, and means supporting the plate at an angle for the application of the person's head tilted sidewise, said means including upper and lower channel elements for the wall chest bracket of conventional X-ray photographic equipment, a constricted extension from the upper part of the plate adapted to seat in the upper channel element, a downward continuation of the extension terminating in the lower channel element, a foot from the continuation adapted to seat in the lower channel element, and a brace between the lower portions of the plate and continuation.
